WILLIAM A. GELLER AND FERN D. HUNT, OF LOS ANGELES, CALIFORNIA.

PAPER-SUPPORT AND ADJUSTABLE-STOP ATTACHMENT FOR TYPE-WRITERS.

1,248,102.

Specification of Letters Patent. Patented Nov. 27, 1917.

Application filed August 14, 1916. Serial No. 114,768.

To all whom it may concern:

Be it known that we, WILLIAM A. GELLER and FERN D. HUNT, citizens of the United States, residing at Los Angeles, in the county of Los Angeles and State of California, have invented new and useful Improvements in Paper-Support and Adjustable-Stop Attachments for Type-Writers, of which the following is a specification.

10 This invention relates to a paper support and an adjustable paper stop for typewriters.

It is an object of this invention to provide a stop for attachment upon a typewriter which will act in coöperation with the paper to determine the spacing of the printed matter and the point of its conclusion at the bottom of the sheet.

Another object of this invention is to provide an attachment which may be readily applied to most typewriters and which may be used without alteration of the typewriting machine.

Another object is to provide a stop attachment which may be detachably mounted upon the typewriter and which is provided with adjustable guide means.

Another object is to provide a stop attachment to be mounted upon a typewriter which will act coöperatively with the platen roll to visibly notify the typist when a certain predetermined point throughout the length of the paper has been reached.

Another object is to provide a stop for use upon typewriters which will act to support the sheet of paper being written upon in a manner to allow the typist to view the entire printed page at all times.

Another object is to provide an adjustment means for the stop which adjustment will be simply and effectively made without the use of auxiliary clamping members.

A further object is to provide a paper stop attachment for typewriters which will be simple in construction, cheap to manufacture, and not liable to get out of order.

Other objects will appear hereinafter.

The invention is illustrated in the accompanying drawings in which:

50 Figure 1 is a view in perspective illustrating the application of the device as applied to the shield of a typewriter.

Fig. 2 is an assembled view of the paper stop device as seen in front elevation.

55 Fig. 3 is a view in rear elevation of the stop device.

Fig. 4 is a view similar to Fig. 3 and shows a side elevation of the assembled device.

Fig. 5 is a view in transverse section 60 through the clamping means as seen along the line 5—5 of Fig. 3.

Referring to the drawings, 10 indicates a typewriter having a platen roll 11 adjacent the rear of which is mounted a shield member 12, all of which parts may be of common construction.

Mounted upon the upper portion of the member 12 is a paper guide 13 which is the embodiment of this invention and is shown 70 as comprising a pair of clamping jaws 14 and 15 which are adapted to engage and grip the shield member 12 by means of a resilient clamping member 16. The clamping member 16 is here shown as encircling the 75 upper edge of each of the jaws and bearing inwardly against the body portion of each jaw. An aperture 17 is made through the clamping member 16 to accommodate extensions 18 and 19 which are formed integral with the jaw members 14 and 15, respectively. The extension 18 has mounted upon it a paper supporting frame 20 which is here shown as comprising a pair of complementary triangular wire members 21 and 22. The members 21 and 22 are formed substantially in the shape of triangles having their altitudes 23 lying adjacent and parallel to each other forming a pair of spaced 85 guide wires. The ends of the wire of which the altitude of each triangle is formed are secured upon the extension 18 of the jaw member 14. The wire forming the base portions 24 of the triangles is bent outwardly and in opposite directions, said portions extending an equal distance at each side of the center line which lies between the altitudes of the angles. The hypotenuse wires 25 of the triangles converge and have their terminating ends secured with their opposite ends to the extension 18 of the jaw member 14 by means of a band 26 which encompasses the extension 18 and the ends of the wire and which is held in position by means of rivets 27 and 28.

105 It will thus be seen that the arrangement and disposition of the wires constituting the altitudes of the two triangles form a guideway for an adjustable guide or stop finger 29 which is slidably mounted thereupon by 110 means of mounting or bearing members 30 and 31 formed integral with the body of the

finger. Attention is here directed to the fact that the distance between the longitudinal passages formed through the members 30 and 31 is less than the normal distance between 5 the centers of the two wire portions 23 upon which they are mounted. This arrangement insures that the finger 29 will be resiliently bound at any point along its travel due to the spring of the two wire portions 23 as they tend to separate and assume 10 their normal parallel relation. This action is particularly illustrated in the transverse section disclosed in Fig. 5 of the drawings in which the dotted lines indicate the normal 15 position of the wires which are placed under tension when brought to the full line position.

When the device is to be used, the extensions 18 and 19 of the jaw members are 20 pressed toward each other, this acting to open the jaws against the action of the spring member 16. The edge of the shield 12 is then inserted between the jaws with the member 19 extending downwardly when 25 released. The binding action of the spring member 16 will cause the jaws to forcibly grip the shield 12 and hold the device in position thereon. As shown in Fig. 1, the paper supporting member 20 will extend upwardly and outwardly from the shield in a 30 manner to support the paper flat in a visible position before the typist. The finger member 29 may then be moved up or down the length of the spring wire guide portions 23 35 until the paper engaging tang or stop 32 is in proper position to indicate the point of conclusion of the printed matter upon the sheet. The opposed resiliency of the wire members 23 will act in opposition to each 40 other within the members 30 and 31 to hold the finger 29 at any point desired, both against sliding and turning movement.

When the device is used, the sheet of paper within the machine will move upwardly 45 and outwardly over the paper support 20,

until the upper marginal edge of the sheet abuts against the stop 32 formed on the end of the guide finger 29. When this point is reached the desired length of written matter will have been printed upon the sheet. Further rotation of the platen roll will cause the sheet to buckle in a manner to visibly notify the typist that the predetermined conclusion of the page has been reached. It will be seen that even though the typist 55 has given no attention to the relation between the upper edge of the paper and the engaging stop portion 32, the buckling action of the paper will instantly act as a warning. 60

It will thus be seen that we have provided a paper stop attachment for typewriters which is extremely simple in construction and operation and which will readily and positively act as a stop in determining in 65 an automatic manner the conclusion of the printed matter on a sheet being typewritten.

We claim:

A paper support and adjustable stop for typewriters comprising a clamp adapted to 70 engage the typewriter shield, a pair of complementary triangular wire members mounted side by side with two adjacent wires in parallel position and the ends of the wires rigidly fixed to one jaw of the clamp, a stop 75 body, parallel bearings rigid with the stop body and slidably mounted upon the parallel wires, and a stop finger extending upwardly from the stop body; said triangular wires serving to support the printed 80 paper as it comes from the typewriter and said stop finger being adjustable and in position to be engaged by the top edge of the printed sheet to indicate when a desired amount of printing has been done. 85

In testimony whereof we have signed our names to this specification.

WILLIAM A. GELLER.
FERN D. HUNT.
